DISH HOLDING RACK

Edward L. Blakeslee, Oak Park, Ill., assignor to G. S. Blakeslee & Co., Chicago, Ill., a corporation of Illinois

Application June 1, 1951, Serial No. 15,368

Term of patent 7 years

(Cl. D44—29)

To all whom it may concern:

Be it known that I, Edward L. Blakeslee, a citizen of the United States of America, residing at Oak Park, in the county of Cook and State of Illinois, have invented a new, original, and ornamental Design for Dish Holding Rack, of which the following is a specification, reference being had to the accompanying drawing, forming a part thereof.

In the drawings:

I claim:

The ornamental design for a dish holding rack, as shown.

EDWARD L. BLAKESLEE.
